(57) **CLAIM**

The ornamental design for a freestanding digital display unit as shown and described.

DESCRIPTION

FIG. 1 is a top front perspective view of a freestanding digital display unit showing our new design;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a top front perspective view of a second freestanding digital display unit showing our new design;

FIG. 10 is a bottom front perspective view thereof;

FIG. 11 is a front view thereof;

FIG. 12 is a rear view thereof;

FIG. 13 is right side view thereof;

FIG. 14 is a left side view thereof;

FIG. 15 is a top plan view thereof;

FIG. 16 is a bottom plan view thereof;

FIG. 17 is a top front perspective view of a third freestanding digital display unit showing our new design;

FIG. 18 is a bottom front perspective view thereof;

FIG. 19 is a front view thereof;

FIG. 20 is a rear view thereof;

FIG. 21 is right side view thereof;

FIG. 22 is a left side view thereof;

FIG. 23 is a top plan view thereof;

FIG. 24 is a bottom plan view thereof;

(Continued)

FIG. 25 is a top front perspective view of a fourth free-standing digital display unit showing our new design;
 FIG. 26 is a bottom front perspective view thereof;
 FIG. 27 is a front view thereof;
 FIG. 28 is a rear view thereof;
 FIG. 29 is right side view thereof;
 FIG. 30 is a left side view thereof;
 FIG. 31 is a top plan view thereof; and,
 FIG. 32 is a bottom plan view thereof.
